GLASS FIBER DRAWING DEVICE

Joseph F. Courtney, Evanston, and Adelbert C. Radtke, Oak Park, Ill., assignors to International Harvester Company, a corporation of New Jersey

Application May 11, 1951, Serial No. 225,882

16 Claims. (Cl. 49—17)

1

This invention relates to the production of thermoplastic fibers and more particularly to novel means for attenuating glass fibers.

The extreme fragility and low tensile strength of individual glass fibers have posed serious problems in the development of a satisfactory drawing means which would provide an even, substantially continuous pull on the fibers without impressing high transverse stresses on the same such as would deform and materially weaken them, or without destructively concentrating the pulling forces on small areas of the fibers.

A general object of the invention is to devise novel drawing means adapted to grasp the fibers along an extensive length thereof under light pressures with a continuous yieldable and preferably sinuous or curved surface whereby a positive drawing effect is achieved.

Another object is to devise a compact and effective drawing apparatus which is inexpensive to manufacture and relatively simple to operate.

A more specific object is to design such apparatus wherein the glass fibers are received between opposed flexible diaphragms which are deflected at the grasping zone to sinuate the fibers along an undulant route in the process of drawing and thereby obtain a positive and effective light grasp on the fibers along an extensive length thereof.

A further object is to provide novel guide means for directing the fibers between the diaphragms when the drawing is initiated.

A still further object is to devise novel stripper means to facilitate discharging of the fibers from the drawing mechanism.

A different object is to effect a compact arrangement wherein the deflecting means for the diaphragms form convenient enclosures for the drives of the drawing assembly.

These and other objects of the invention will become more apparent from the specification and the drawings, wherein:

Figure 1 is a fragmentary side elevational view of one form of drawing mechanism with environmental structure shown diagrammatically.

Figure 2 is a fragmentary top plan view of the drawing mechanism.

Figure 3 is a further top plan with the guide means removed.

Figures 4 and 5 are enlarged bottom and top plan views respectively of Figure 3, and

Figure 6 is a fragmentary front edge view, and

Figure 7 is a top edge view partially in radial

cross-section of another form of the invention.

Describing the invention in detail and referring first to the embodiment shown in Figures 1 through 6, the furnace 2 which contains molten glass comprises a bottom apertured bushing or plate 4 through which a plurality of filaments 6, 6 flow gravitationally. These filaments are gathered together by a workman who draws them over an applicator assembly 10 adapted to apply to each filament a suitable coating preferably of a plastic material. The filaments are spread in a fan arrangement from the furnace due to the spacing of the apertures therein, and past the applicator are converged into a groove 12 of a gathering sheave 14 which is rotatably mounted on a shaft 16. The filaments enter groove 12 before the coatings have congealed in order to obtain adherence between all of the filaments whereby they are associated into a strand 18.

The strand 18 is passed over a guide wheel 19. The guide wheel is formed with a guide surface 21 which is eccentric to the axis of rotation of the wheel 19 and serves to shift the strand 18 transversely for a purpose hereinafter explained.

The strand is then passed through a guard or guide member 20 of a drawing mechanism generally indicated 22. The guide member 20 is formed of sheet metal which is folded to provide diverging side panels 24, 24 defining an outwardly flaring strand-receiving mouth 26 which at the apex 28 of the fold leads into a slit 30 formed by an arcuate cut out 32 in the back side of member 20 through the apex thereof intermediate its ends.

The slit opens in radial alignment with a strand-receiving gap 34 formed in the periphery of a rotating drawing member 35 by and between two axially spaced annular flexible diaphragms or grasping members 36 and 38, said diaphragms extending radially outwardly of the outer periphery of a separator plate 40 therebetween. The diaphragms are preferably made of rubber fabric reinforced or the like and are held against opposite sides of the separator 40 by interconnected annular clamp members 44, 44 pressed against the remote sides of the diaphragms.

The member 35 has its strand grasping section or region entered into the cut out 32 of the guide and is driven in any suitable manner through a shaft 46.

The member 35 is associated at its grasping zone with two deflecting discs 48 and 50 located at opposite sides thereof and preferably rotatable on axes converging towards the member 35.

Each disc 48 and 50 is provided with a periph-

eral frusto-conical face 52 which is beveled radially inwardly with respect to member 35.

As seen in Figure 6, the disc 48 is positioned at a slightly higher level than disc 50 and on its face 52 engages as at 54 with the outer side of the diaphragm 36 deflecting it axially towards the opposite side of member 35. Similarly, disc 50 engages on its face 52 as at 56 with the outer side of diaphragm 38 deflecting the same axially towards the opposite side of member 35. It will be noted that each segment of the diaphragm contacted by the associated disc assumes the arcuate contour of the engaging surface 52, and this closes the gap 34 and thus clasps the strand 18 against the contiguous segment of the opposing diaphragm with accompanying deflection thereof. Preferably the surface 52 on each disc is tangential to the central radial plane of the drawing member 35.

It will be readily observed that the strand 18 is situated through the drawing means 35 which thus obtains a positive grasp on the strand and which is amplified by a wedging tendency between the strand and the opposing radial surfaces on the diaphragms in view of the curvature thereof transversely of the strand. The bevel of the surfaces 52 is designed to obtain rolling contact without slippage along the full area of engagement with the related diaphragms in view of the disparity in the speeds of concentric increments of the diaphragms radially inwardly from the peripheries.

A stripper element 58 (Figure 1) is located at the lower or discharge extremity of the gripping zone; said element comprising a blade 60 supported in substantially vertical position and connected at its lower end together with the lower end of the guide element to a suitable framework 62.

The blade 60 is entered between the diaphragms 36 and 38 and comprises at its upper extremity a curved section 64 presenting on its leading upper edge a curved surface or face 66 which is directed upwardly inwardly of the diaphragms 36 and 38 and is terminated adjacent to the outer perimeter of the separator plate.

It will be understood that deflection of the diaphragms is accompanied by pressing the air out from the gap 34 at the grasping zone of the drawing assembly. As the assembly is rotated the increments of the diaphragms moving out of the grasping zone are caused to separate due to centrifugal action as well as the restorative nature of the material composing the same. As the diaphragms begin to open the air rushes into the void created and attempts to blow the strand radially inwardly into the gap. However, during the interval the momentum of the strand, which causes it to discharge substantially tangentially to the assembly, prevents substantial deflection of the strand from its discharge course. The air splits about the strand and rushes around the same into the portion of the gap therebehind. This air frictionally engages and is carried downstream between the spaced diaphragms and strikes the leading face of the blade inwardly of the strand to create a radially outwardly moving air cushion sliding off the leading face 66 of blade 60 to release the strand. The forwardmost extremity of the leading end of the blade is disposed adjacent to the radially inner peripheries of the diaphragms and the leading edge then recedes arcuately downstream of said leading end towards the outer peripheries of said diaphragms. The blade, which extends from adjacent the inner

edge of the gap 34 to the outer edge thereof, substantially completely fills the space between the diaphragms without abrasion and the contour of the leading edge of the blade causes the air to pile up and progress downwardly over the leading edge of the blade to produce a blowing effect radially outwardly of the diaphragms and directed against the inner side of the strand so as to blow it away from the blade or stripper, whereby the strand is prevented from abrading thereagainst. Without the stripper the strand would be urged into the drawing element and continue to wrap therearound. The eccentricity of the guide surface 21 of wheel 18 changes the pitch of the strand and shifts it radially with respect to the gripping surfaces to prevent the formation of a narrow groove in the working faces of the diaphragms. The strand may discharge into a suitable container below after being discharged from the drawing means.

Referring now to the embodiment in Figure 7, the drawing means 100 comprises an annular assembly 102 including a central separator ring 104 flanked by a pair of resilient annular diaphragms 106, 106 of preferably fabric reinforced rubber or the like, said diaphragms extending radially outwardly of the separator ring and being clamped together by a pair of clamp members 108 which may be suitably interconnected as by rivets 110, 110. Each clamp plate 108 is secured on its outer side to a pulley 112 rotatably mounted on a common stationary shaft 114, the pulleys being driven by V-belts 116 from any convenient power source.

The shaft 114 is connected to a framework 120 for supporting the assembly. Stub axles 122 and 124 may be integral with shaft 114 but are preferably rotatably and adjustably mounted with respect thereto and extend outwardly of the framework 120 and are arranged in radially outwardly diverging relationship with respect to the axis of shaft 114.

The assembly 100 is flanked by a pair of dished, annular deflecting discs 126 and 128 each of which is preferably formed of sheet steel and comprises a depressed or dished central body portion 130 riveted to a hub 132 rotatably mounted on the associated stub axle 122 or 124 and retained thereon as by a nut 134 on the outer end of the axle. A generally radial flange 136 encircles the body portion 130 of each clamping disc.

It will be observed that the disposition of the axles 122 and 124 positions the discs 126 and 128 in converging relationship toward one end of a determined diameter of the assembly and that the discs diverge towards the other end of the diameter. The discs at their convergence have their radial flanges, which are preferably outwardly turned at their outer perimeters as at 138, pressed under predetermined light pressure against the outer side of the adjacent diaphragm. This action of both clamping discs effects a light, continuous and positive grasp through a flexible medium against the strand 140 which is entered into the gap 142 between the diaphragms 106, 106 upstream of the grasping area of the drawing assembly. The drawing assembly may be associated with a stripper member 58 (not shown) which as in the previous embodiment may be positioned between diaphragms 108, 108.

It will be understood that a friction drive for discs 126, 128 is obtained through engagement with the diaphragms. The axes of rotation of these discs converge towards shaft 114 in the plane of the surface of the drawing of Figure 7,

however to produce a sinuous effect the axles 122 and 124 are disposed at different levels to obtain engagement of the flange of one disc slightly downstream of the other whereby the diaphragms and the strand are situated through the S-pattern grasping zone. This effects an amplification of the grasp on the strand as heretofore discussed.

It will be understood that the grasping area may be modified in either embodiment to meet specific conditions by adjusting the relative positions of the grasping or diaphragm deflecting means so that the means may be located to provide directly opposed pressures or widely separated pressure areas.

The stripping means in either embodiment may be such as shown in our copending U. S. application for Glass Fiber Drawing Mechanism and Process, Serial No. 221,596, filed April 18, 1951.

What is claimed is:

1. In apparatus for attenuating elongatable materials, a circular structure comprising a pair of circumferentially extending flexible diaphragms defining a material receiving gap therebetween, means for rotating the structure, and means for deflecting said diaphragms axially to close the gap and grasp the material therebetween and comprising a pair of discs receiving said diaphragms therebetween and each having its peripheral face pressed into the external side of the adjacent diaphragm and each rotating on an axis angularly related to the axis of rotation of the structure.

2. Apparatus according to claim 1 wherein the area of engagement of one disc with the related diaphragm is spaced circumferentially of the area of engagement of the other disc with its related diaphragm.

3. In apparatus for attenuating thermoplastic materials, a pair of opposed circumferential drawing surface means adapted to receive the material therebetween and movable axially towards and away from each other, means for driving said surface means, and biasing means for moving at least one surface means towards the other for grasping the material, said biasing means comprising elements rotatably mounted outwardly of said surface means and having rolling contact therewith at circumferentially spaced contiguous areas.

4. In apparatus for attenuating thermoplastic materials, a pair of opposed circumferential drawing surface means adapted to receive the material therebetween and movable axially towards and away from each other, means for driving said surface means, and biasing means for moving at least one surface means towards the other for grasping the material, said biasing means comprising a pair of discs disposed outwardly of said surface means and arranged in radially converging relationship with said surface means and in rolling pressing contact therewith, and having circumferentially extending areas on the sides thereof in engagement with the respective surface means.

5. Apparatus for attenuating elongatable fibers comprising spaced flexible grasping means presenting surfaces adapted to receive the material therebetween and carrying an impinging air stream therealong, means for clamping said grasping means against said material, means for rapidly moving said grasping means, and means downstream of said clamping means for stripping the material from said grasping means and comprising a member having a face disposed in immediate proximity to said moving surfaces

athwart the air stream carried along said surfaces, said face oriented to produce with said air stream a blowing effect outwardly of said grasping means for discharging material therefrom.

5 6. Apparatus for attenuating elongatable material comprising a drawing structure including a wheel having a peripheral gap flanked by axially movable grasping elements, means for biasing said elements to effect a grasping action against the material in a determined zone of said structure, and guide means for entering said material into the gap upstream of said zone and comprising a pair of side surfaces converging towards said gap and defining a slot therebetween in radial alignment with said gap and positioned in proximity thereto.

10 7. In apparatus for attenuating thermoplastic material, opposed circumferential drawing surfaces rotatable about a given axis and movable 20 towards and away from each other and adapted to receive the material therebetween, means for sinuating said surfaces while clamping the same against the material and comprising oppositely acting counterparts deflecting the surfaces in 25 reverse directions at contiguous areas to produce a substantially S-pattern grasping zone, and means for driving said surfaces.

8. Apparatus for attenuating thermoplastic material comprising a revolving circumferential 30 surface adapted to accept the material thereagainst, means for pressing the material into intimate contact with the surface, means for driving the surface, and means for stripping the material from the surface and including an edge 35 positioned in cleaving relationship to the surface and said first mentioned means.

9. In an apparatus for attenuating elongatable material, a circular structure including a pair of resilient elements spaced apart axially to 40 define a material-receiving circumferential gap therebetween, a biasing assembly positioned along the remote sides of said elements and arranged to bear against said elements along a part of the circumferential extent thereof to deflect said elements towards each other in this zone 45 and thus effect a gripping action on the material entered within said gap upstream of the zone, means for driving said elements, and guide means having faces converging toward the gap for directing the material thereto.

10. In apparatus for attenuating glass issuing from a source in a plurality of filaments, means associating the filaments into a strand, drawing means effecting a continuous pulling force 55 on the strand for attenuating said filaments and comprising a pair of opposed flexible rotatable grasping members presenting circumferential drawing faces on adjacent sides, rotatable clamping means arranged to engage each member on its external side in a predetermined region to deflect the member axially towards the other and effect a clasping action therewith against the strand, said strand directed substantially circumferentially of said faces, the area 60 of engagement of said clamping means with one of said members being disposed downstream in the direction of travel of the strand with respect to the area of engagement of said means with the other of said members and said areas of engagement being disposed in contiguous relationship.

11. In a drawing apparatus, a pair of rubber-like diaphragms arranged side by side and rotatable on a common axis, and normally spaced 70 apart axially to define a material receiving gap

therebetween, means pressing portions of said diaphragms together to effect a grasp on the material, and stripping means downstream of said portions for discharging said material from said drawing apparatus and comprising a blade extending between said diaphragms.

12. A combination according to claim 11 wherein the leading edge of said blade is curved in a downstream direction from its radially inner edge to its radially outer edge and arranged to direct the air moving with the diaphragms along said edge to produce a blowing effect against the inner side of the material to blow it radially outwardly of the gap.

13. Apparatus for attenuating thermoplastic materials comprising a drawing surface, means for guiding the material to the surface, means for biasing the material against the surface, and means for stripping the material from said surface and presenting a face disposed along said surface in intercepting relationship to the air moving with the surface to produce a blowing effect therewith in a direction toward the outer periphery of the surface to discharge the materials therefrom.

14. Material attenuating apparatus including a rotatable drawing assembly having peripheral strand grasping means, and driving means for rotating the assembly, said grasping means enclosing said driving means and disposed to at least partially shield the same.

15. Material attenuating apparatus compris-

ing a rotatable drawing assembly, material grasping means including rotatable elements at opposite sides of the assembly and arranged in converging planes towards one end of a determined diameter of the assembly, and driving means for the assembly extending from between the diverging extremities at the opposite end of said diameter.

16. In material attenuating apparatus, a rotatable drawing assembly, a pair of side elements flanking said assembly, a sheave between said elements shielded thereby and connected coaxially with the assembly, and driving means for the assembly trained about the sheave and extending outwardly of said elements substantially radially with respect to the axis of rotation of the assembly.
